WILLIAM A. CHAMBERLIN, OF ALEXANDER, NEW YORK.

Letters Patent No. 78,184, dated May 26, 1868.

IMPROVED BED-BOTTOM.

The Schedule referred to in these Letters Patent and making part of the same.

TO ALL WHOM IT MAY CONCERN:

Be it known that I, WILLIAM A. CHAMBERLIN, of Alexander, in the county of Genesee, and State of New York, have invented certain new and useful Improvements in Bed-Bottoms; and I do hereby declare that the following is a full and exact description thereof, reference being had to the accompanying drawings, in which—

Figure I is a longitudinal vertical section of a bedstead provided with my improved bottom.

Figure II is a plan thereof.

Like letters of reference designate corresponding parts in both figures.

My invention consists,

First, in the special combination and arrangement of rubber springs, with supporting cross-pieces and levers for sustaining the slats.

Second, in the peculiar manner of hinging the ends of the levers to the said cross-pieces.

In the drawings, A A represent the ordinary wooden slats of a bed-bottom. B B, levers, on the ends of which the ends of each slat rest. C C are two cross-pieces, secured in any suitable manner to the rails of the bedstead, to which the ends of the levers B are hinged.

The cross-pieces C are formed with transverse recesses; d d, in their upper surface, for the reception of the ends of the levers, which are bevelled, as shown at e. A hook-bolt, f, passes through the ends of each lever and the cross-piece, with a key-rod, g, of any suitable material, passing through the eyes of the said bolts, and extending transversely across the bedstead and ends of the levers, while a nut, i, or other fastening on the under side of the cross-pieces, firmly secures the bolts and key-rod in place. This forms a cheap and reliable hinge for the levers.

Immediately back of the hinge, in a suitable socket in the recesses d, are arranged blocks of India rubber, s, or equivalent elastic material, which operate as springs when the levers are depressed thereon by the pressure of the slats on the ends of the levers, as is clearly represented in the drawings.

One or both ends of the slats are formed with a longitudinal slot, m, with a screw fitting in the same, and screwing into the ends of the levers, with the heads of the screws countersunk flush or slightly beneath the surface of the slats, to prevent their wearing the mattress. This mode of connection prevents the vertical as well as lateral displacement of the slats, while the slot permits that longitudinal yielding of the ends of the slats, and play of the levers, necessary, and consequent to their elastic or springing action.

The elastic fulcra, which the rubber blocks form, by slightly yielding, produce at the end of the relatively long arms of the levers, the most ample vertical play required.

The key-rod g, by pressing on the ends of all the levers, forms a single fastening, which holds the levers more steadily in place than could be accomplished by an independent fastening for each. Another advantage of this is, that in case any one of the bolts becomes loose, the extended key held by bolts adjacent the loosened one, will keep the intermediate lever in place, and maintain it in efficient action.

What I claim as my invention, and desire to secure by Letters Patent, is—

1. The hinged levers B B, supporting cross-pieces C C, India-rubber blocks s s, and slats A A, arranged and operating substantially in the manner and for the purpose set forth.
2. Hinging the ends of the levers to the cross-piece by means of hook or eye-bolts f; and extended key-rod g, in the manner and for the purpose shown and described.

WM. A. CHAMBERLIN.
